UNITED STATES PATENT OFFICE.

GEORGE W. NEWMAN, OF CHICAGO, ILLINOIS, ASSIGNOR TO WILSON-JONES LOOSE LEAF COMPANY, A CORPORATION OF ILLINOIS.

TRANSFER BINDER.

Application filed October 27, 1921. Serial No. 510,869.

To all whom it may concern:

Be it known that I, GEORGE W. NEWMAN, a citizen of the United States, and a resident of the city of Chicago, in the county of Cook and State of Illinois, have invented certain new and useful Improvements in a Transfer Binder; and I do hereby declare that the following is a full, clear, and exact description of the same, reference being had to the accompanying drawings, and to the numerals of reference marked thereon, which form a part of this specification.

This invention relates to a loose leaf transfer binder of the type especially adapted for shipping receipts or the like.

It is an object of this invention to provide simple, economical and easily operable locking means for firmly securing the upper cover on the device in any adjustable position.

It is a further object of this invention to provide a pair of spring-pressed levers which cooperate with the impaling posts to lock the binder in any adjusted position.

With these and other objects in view which will become more apparent in the following description and disclosure, this invention comprises the novel mechanism and combination hereinafter described and more particularly pointed out and defined in the appended claims.

In the accompanying drawings which illustrate a preferred embodiment of my invention and in which similar reference numerals refer to similar features in the different views:

Figure 1 is a top plan view of a binder embodying my invention.

Figure 2 is a rear elevation thereof.

Figure 3 is a section on the line 3—3 of Figure 1 upon an enlarged scale.

Figure 4 is a fragmentary section upon an enlarged scale illustrating the spring-pressed levers in inoperative position.

Figure 5 is a fragmentary side elevational view of the structure shown in Figure 4.

Figure 6 is an enlarged plan view of an anchor plate for securing the levers.

In referring to the drawings, it will be

observed that I have illustrated a binder having a base or bottom clamping member 1, preferably made of metal and provided with appropriately spaced screw-threaded sockets in which the cylindrical impaling posts 2 are secured. In order that these posts may be properly screwed into the base, their upper ends are provided with flat surfaces formed by cutting grooves at diametrically opposite points whereby a tool may be readily applied. An upper clamping member 3, preferably of metal and provided with spaced slots for receiving the impaling posts, cooperates with the bottom clamping member to clamp the leaves therebetween. Suitable covers 3^a, preferably of the rigid cardboard type and sheathed in fabric, are hinged to the clamping members preferably by continuing the fabrics rearwardly and sheathing the clamping members therewith as is well known in the art.

In the use of this binder, the upper cover and clamping member are removed and the leaves impaled upon the posts 2. Thereafter the upper cover and clamping member are replaced, pressed upon the levers, and clamped to the impaling posts. As loose sheets are constantly being thuswise added and removed from the binder, it is desirable that the upper cover locking means should be readily and quickly operable and should be of such a durable character as to withstand the constant and severe usage to which a binder of this type is frequently put. In accordance with my invention, I have provided a pair of locking levers 4, preferably of metal, having rounded notches 5 in their outer ends which cooperate with the impaling posts 2, the levers being extended at one side of the notches to provide finger gripping portions 6 which are bent upwardly to a slight degree whereby the same may be readily grasped by the fingers for raising the levers from their locking engagement with the impaling posts.

The inner ends of the levers are provided with integral hinge members which consist of tongues 7 provided with aligned lateral lugs 8 which extend to the rear ends of the

tongues 7, thuswise providing T-shaped lugs which are adapted to fit in the T-shaped slots 9 formed in the ends of an anchor plate 10. The entrance notches of these slots are designed to accommodate the tongues 7. The anchor plate 10 is secured upon the upper clamping member midway between the impaling posts so that when the levers are in their operative clamping positions, the lugs 8 will lie in the T-shaped slots and in contact with the upper surface of the clamping member 3, the tongues 7 lying in the entrance slots. A spring plate 11 having notches 12 in its ends designed to accommodate the tongues 7 and of a size equal to the anchor plate 10 is super-imposed upon the anchor plate 10. The two plates 10 and 11 are secured preferably by rivets along the transverse center line to the clamping member 3, allowing the upper plate to flex.

With reference to Figures 3 and 4, it will be noted that the tongues 7 slope upwardly from the lugs 8 to a slight degree and that the levers 4 slope downwardly to a slight degree from the tongues 7 to the gripping notches bringing thereby the upper surfaces of the levers and the spring plate into better alignment and improving the appearance of the binder.

When the levers 4 are in their clamping position, the rear ends of the tongues 7 and lugs 8 abut against the respective rear walls of the T-shaped slots in the anchor plate 10 and the spring plate 11 rests upon the anchor plate and against the levers 4 and retains the levers in yielding, gripping, or binding relation with the impaling posts 2, which are pressed against the opposite walls of the slots, thereby holding the upper cover firmly on the leaves in adjusted position. When it is desired to remove the upper cover, the finger pieces 6 of the levers are grasped and the levers are raised to the position shown in Figure 4, the spring plate 11 yielding for this purpose. When the levers are raised into vertical position, the lower edges of the tongues 7 and lugs 8 will rest firmly upon the clamping member 3, and the spring plate 11 which bears down upon the upper edges of the lugs 8 will hold the levers 4 in vertical position.

It will accordingly be apparent that I have invented an efficient binder locking mechanism that is simple, durable, easy to operate, and which is retained in its inoperative position by spring pressure, so that the upper cover can be readily adjusted to tightly clamp the loose sheets without any interference of the locking mechanism. In other words, the locking levers 4 are held in inoperative position until it is desired to finally lock the upper cover in adjusted position.

I am aware that many changes may be made, and numerous details of construction

may be varied through a wide range without departing from the principles of this invention and I therefore do not purpose limiting the patent granted otherwise than necessitated by the prior art.

I claim as my invention:

1. In a loose leaf binder having a lower clamping member and a pair of impaling posts thereon, an upper clamping member having a slotted anchor plate secured thereon, a pair of levers having lugs at their inner ends fitting in the slots of said anchor plate, and notches upon their outer ends adapted for receiving said impaling posts, and a spring plate superimposed upon said anchor plate.

2. In a loose leaf binder having a lower clamping member with a plurality of impaling posts thereon, an upper clamping member having apertures for receiving said impaling posts, a pair of levers cooperating with said impaling posts to lock the upper clamping member to said posts, an anchor plate to which the rear ends of said levers are anchored, and a spring plate resting upon said levers and co-operating therewith for holding said levers in operative or inoperative position.

3. In a loose leaf binder having a lower clamping member provided with a plurality of impaling posts thereon, an upper clamping member a plurality of levers frictionally pressing against said posts, and means comprising a resilient member for pivotally anchoring said levers to said upper clamping member.

4. In a loose leaf binder, an upper clamping member adapted for receiving impaling posts, an anchor plate having T-shaped slots in opposite edges thereof secured to said member, clamping levers having T-shaped lugs fitting in said T-shaped slots, and a spring plate superimposed over said anchor plate and secured to said member, said spring plate being effective to hold said levers in inoperative position or in operative relation with said impaling posts.

5. In a loose leaf binder having a lower clamping member provided with a pair of impaling posts, an upper clamping member adapted for receiving said posts therethrough, an anchor plate attached to the upper clamping member and having end recesses, levers having their inner ends pivotally confined in said recesses and their outer ends fashioned for engaging said posts, and resilient means yieldingly retaining the inner ends of said lever in the recesses of said anchor plate.

6. In a loose leaf binder having a lower clamping member provided with a pair of impaling posts, an upper clamping member adapted for receiving said posts therethrough, a pair of levers pivotally secured to said upper clamping member and adapted

for engaging said impaling posts for locking said upper clamping member with respect thereto, said levers being swingable to an upright position out of engagement
5 with said posts, and yielding means cooperating with said levers for holding the same in said upright position.

In testimony whereof I have hereunto subscribed my name in the presence of two subscribing witnesses.

GEORGE W. NEWMAN.
